(57) **CLAIM**

The ornamental design for a display screen with graphical user interface as shown and described.

DESCRIPTION

The patent or application file contains at least one drawing executed in color. Copies of this patent or patent application publication with color drawing(s) will be provided by the Office upon request and payment of the necessary fee.

1. Display screen with graphical user interface

1.0: Front view

The exterior even-length broken lines illustrate portions of a display screen and form no part of the claimed design. The remaining even-length lines illustrate portions of the graphical user interface and form no part of the claimed design. The broken line text forms no part of the claimed design. The characteristic features of the design lie in the shape and pattern of the graphical user interface as shown.
